UNITED STATES PATENT OFFICE.

CHARLES H. ANDERSON, OF CINCINNATI, OHIO.

WINDOW-SASH CONSTRUCTION.

1,273,715.

Specification of Letters Patent Patented July 23, 1918.

Application filed June 28, 1916. Serial No. 108,407.

To all whom it may concern:

Be it known that I, CHARLES H. ANDERSON, a citizen of the United States, and a resident of Cincinnati, in the county of 5 Hamilton and State of Ohio, have invented certain new and useful Improvements in Window-Sash Construction; and I do hereby declare the following to be a full, clear, and exact description of the invention, such 10 as will enable others skilled in the art to which it appertains to make and use the same.

This invention relates to improvements in sash structures,—more particularly to such 15 as are employed for car windows,—and the invention consists in certain novel features of construction and combinations of parts as hereinafter set forth and pointed out in the claims.

20 In the accompanying drawings; Figure 1 is a view in elevation partly broken away, of one embodiment of my invention; Fig. 2 is a view showing one of the upper corner brackets and its connection with the right 25 hand sash rail in section; the edge portions of lower right hand corner bracket and its connection with the rail being shown in elevation; Fig. 3 is a longitudinal sectional view through the lower right hand corner 30 bracket containing the locking device; Fig. 4 is an inside edge view of the same corner bracket; Fig. 5 is a sectional view on the line 5—5 of Fig. 3; Fig. 6 is a sectional view on the line 6—6 of Fig. 3; Fig. 7 is a 35 sectional view on the line 7—7 of Fig. 10, showing the structure of one of the upper corner brackets when wooden rails are used; Fig. 8 is a sectional view showing the guide and weather strip devices on two adjacent 40 sashes (when wooden rails are used) at respective sides of the window post of the car; Fig. 9 is a separate face view of the fixed finger lift plate; Fig. 10 is a face view, partly broken away, and Fig. 11 is an 45 edge view partly broken away, showing the application of my improvements in a sash having wooden rails; Fig. 12 is a sectional view through a window post and the metal rails of two sashes; Fig. 13 is a sectional 50 view through the metal base rail and the window sill; Fig. 14 is a perspective view, partly in section, of one of the metal rails of the sash and Fig. 15 is a sectional view 55 showing the upper metal rail of a lower sash and the lower metal rail of an upper sash.

1 represents a sash comprising side rails

2, bottom and top rails 3, 4 and corner brackets 5, 6. In the embodiment of my invention shown in Figs. 1 and 2, the rails as well as the corner brackets are made of metal, and 60 are constructed and united in a manner which will presently be explained. The two upper corner brackets 5, are the same in construction, as are also the several rails, but the lower right hand corner bracket embodies 65 certain additional structural features to adapt it for the accommodation of locking and lifting devices, and the lower left hand corner bracket may also be adapted for the reception of lifting means. 70

Each corner bracket is made of metal, preferably aluminum, and cast hollow, forming chambers in which cork or other insulating material 7 may be packed. The members 8—9 of each corner bracket are disposed 75 at right angles to each other and each of said members is made with integral parallel plates or extensions 10 for the accommodation of the metal sash rails, the latter being adapted to be made to engage seats 11—12 80 formed on the respective members of the bracket between the parallel plates or extensions thereof. These seats 11—12 may be made with openings to permit the insertion of insulating filling 7, and said openings 85 may be closed by suitable plastic material as indicated at 13. The respective plates or extensions of each corner bracket member are provided with inwardly projecting lugs 90 14 having beveled front and rear ends, and the end of a hollow metal sash rail entering between said plates or extensions is formed with recesses 15, 15, to receive said lugs, such recessed portions of the rail being connected by a web 16. Those portions of the 95 plates or extensions 10 having the lugs 14, are perforated for the passage of screws 17 which also pass through suitable holes in the web 16, and in this manner the metal rails are secured to the metal corner pieces. 100 It will be observed that as the lugs 14 on the bracket plates or extensions and the recesses 15 in the rails have beveled coating walls, the rail ends will be urged to their seats in the corner brackets when the screws 105 17 are tightened.

Each hollow rail section is provided at one edge with a glass-retaining lip or flange 18, curved in cross section as clearly shown in Fig. 14, and the inner edge of the respective members of each corner bracket are provided with flange or lip sections 110

19—20, the flanges or lips 18 of the rails being recessed to receive the flange or lip sections 20 on the corner brackets. Thus it will be seen that the flanges or lips 18 of the rails 5 interlock with the alining glass-retaining flanges or lips on the corner brackets.

Each metal rail member (2, 3, 4) is as before stated, made hollow and may contain suitable insulating packing 21 as shown in 10 Figs. 12 and 13, said rail section also having a longitudinal opening 22 for the accommodation of the face portion of a wooden nailing strip 23, the latter being located within the rail section and extending from 15 end to end thereof. The strip 23 is disposed diagonally within the rail section, and is retained in place by means of slotted webs 24 located at intervals with said rail section and in which said strip is seated, as 20 clearly shown in Figs. 12 and 13. Wooden retaining strips 25 are located on the rails and are secured in place by suitable fastening devices 26 (either nails or screws), which pass through said strips 25 and enter 25 the strips 23,—said wooden strips 25 co-operating with the lips or flanges 18 on the rail and the lips or flanges on the corner brackets to retain the glass pane 27 in place.

The upper horizontal rail 4 and the upper 30 corner bracket 5 of the sash are depressed or recessed in the manner indicated at 5* in Figs. 2 and 5, and in these depressed parts of the rail and corner brackets a thin plate 28 (preferably of sheet metal) is secured, 35 said metal plate being curled at its respective edges, as at 29, to retain the respective edges of a bulging or bowed weather strip 30 of rubber, felt or other suitable flexible material. When two sashes are employed, 40 as shown in Fig. 15, the bowed weather strip 30 will engage the inner face of the lower rail of the upper sash and will be forced upwardly and inwardly, as illustrated in Fig. 15, and thus effect an airtight joint 45 between the two sashes.

The bottom edge of the lower sash rail 3 is inclined to engage the inclined face of the sill 31, and said lower edge of the rail may be recessed at 32 (Fig. 13) to receive a folded 50 weather strip 33 secured to the sill and window frame, by means of fastening means 34.

Weather strips 35 are also secured to the vertical rails of the sash and when the sash is in place in the window frame, these strips 55 35 will be folded to U-shape, the folded edge being engaged by a flange or rib 36 on the rail, as shown in Fig. 12. The weather strip 35 is held in place by a metal molding or retaining strip 37, said metal strip lying 60 against the face of the weather strip and is secured to the rail by screws 38. One edge of the molding or retaining strip 37 extends approximately to the folded edge of the weather strip, so that said folded edge will 65 be located between one edge of the strip 37

and the flange or rib 36 of the rail. The molding or retaining strip 37 projects out from between the folds of the weather strip 35 and is formed with a shoulder 39 projecting toward the plane of the free member of 70 the weather strip, and with an extension 40 which engages the inner face of the rail, as shown in Fig. 12.

The weather strips 35 on adjacent sashes form cushions between said sashes and slide 75 or guide brackets 41 secured to the T-bar window post 42 of the car and thus take up play of the sashes and form weather-tight joints. It will be observed that the web and flanges of the T-post are somewhat tapering 80 as shown in Fig. 12 and as posts of such shape do not of themselves form desirable runways for the sashes, and hence the slides or guides 41 constitute valuable features to insure efficient guides. Each slide or guide 85 41 comprises a sheet of metal having a part 43 bent upon itself and securely riveted, as at 44, to the web of the window post so as to form a smooth and flat surface against which the flexible strip 35 may slide. From the 90 outer portion of the part 43, the metal of the guide sheet extends laterally behind one of the flanges of the post 42, as at 45, and is provided with an outwardly projecting rib 46 to engage the inner face of the flange of 95 the post and thus cause the lateral member 45 of the guide sheet to be disposed in a plane at right angles to the transverse axis of the post and parallel with the outer face of the adjacent sash rail 2, so that the latter 100 may have a flat outer sliding bearing relatively to the window post. The guide sheet or bracket 41 is formed at its free edge with a loop 47 which embraces the free edge of 105 the window post flange and the free edge of this loop portion engages the outer face of said post flange. Thus it will be seen that the rib 46 serves an additional function, when co-operating with the loop 47, to grip or clamp the guide sheet to the flange 110 of the T-post.

Instead of making the rails of the sash of metal, as hereinbefore described they may be made of wood as shown at 48 in Figs. 7, 8, 10 and 11. When wooden rails are employed, the corner brackets may be provided with wooden fillers 49 to which portions of the vertical weather strips 35 may be secured by means of wood screws 35*, the other portions of said weather strips being secured to the outer edges of the wooden rails, as shown in Figs. 7, 10 and 11. The fillers 49 also serve as means to which portions of the weather strips 30 may be secured. 115 120 125

The right hand corner bracket 6 is formed with a pocket 50, in which a removable backing 51 of cork or other suitable material may be located. At or near the top of the pocket 50, the end walls of the latter are 130

made with grooves 52 to receive the ends of a finger lift plate 53, said plate being inserted into the pocket so that its inner edge will bear against the cork backing 51. The 5 projecting portion of the lift plate is made with shoulders 54—55 (Fig. 9) which rest against the outer face of the corner bracket. Above the pocketed portion of the corner bracket 6, the latter is made with a bore 56, 10 in which the shank 57 of a sash lock or presser foot 58 is mounted, and the end face of the bracket 6 is made with a recess 59 to receive said lock or presser foot—said recess being open at one side to permit the 15 lock or presser foot to reach the window frame or a suitable engaging device thereon. The shank 57 of the presser foot is provided with a shaft 60 which extends through the bore 56 and is revolvably mounted in a 20 smaller bore 61 in the corner bracket. A coiled spring 62 encircles the shaft 60 and one end of this spring is inserted into a socket 63 in the shank 57,—the other end of said spring being made with a straight portion 25 64 (Fig. 1) to enter a groove 65 (Fig. 2) in the wall of bore 56. The corner bracket 6 is made with a pocket 66 immediately over the pocket 50 and the finger lift 53, for the accommodation of a finger lever 30 67, the latter being made with a sleeve 68 through which the presser foot shaft 60 passes, as shown in Figs. 3 and 6. The sleeve portion of the finger lever is secured to the shaft 60 by means of a screw 69, and 35 to permit ready access to this screw after the parts shall have been assembled, the finger lift plate 53 is made with a hole 70 and the wall of the bore 56 is cut away as shown at 71.

40 I do not claim in this case the novel features of the sash lock and its mountings in the corner bracket, nor the slide or guide devices on the window post and the co-operation of the sashes therewith, as these features 45 constitute the subjects matter of separate applications filed simultaneously herewith and designated by Serial Nos. 106,408 and 106,409.

Having fully described my invention what 50 I claim as new and desire to secure by Letters-Patent, is:—

1. A window sash comprising metal corner brackets, and rails connecting said brackets, each of said corner brackets comprising 55 two integral members disposed at right

angles to each other and each member having parallel plate extensions receiving the adjacent sash rail between them, each plate extension having an inwardly projecting lug and the rail sections having recesses to receive the lugs of the corner bracket extensions, and fastening devices passing through said corner bracket extensions and the rail sections. 60

2. In a window sash, the combination of a metal corner bracket and a sash rail provided with recesses having beveled walls, 65 said corner bracket comprising two members disposed at right angles to each other, each member provided with parallel plate extensions receiving the rail between them, beveled lugs projecting inwardly from said plate extensions and entering the recesses in the rail, and fastening devices passing through said plate extensions and their lugs 70 75 and through said rail.

3. In a window sash, the combination of hollow metal corner brackets, each comprising integral members disposed at right angles to each other, and each member having parallel plate extensions, and metal sash rails having their ends disposed between the plate extensions of the corner brackets and secured thereto. 80

4. In a window sash, the combination of hollow metal corner brackets and hollow metal rails having their ends inserted into said hollow corner brackets and secured thereto. 85

5. In a window sash, the combination of metal corner brackets, of hollow metal rails secured thereto, said hollow rails having elongated slots, and diagonally disposed wooden nailing strips disposed in said hollow rails and closing the slots therein. 90

6. In a window sash, the combination of metal corner brackets, hollow metal rails secured to said brackets, said rails having elongated slots, slotted webs disposed transversely within said hollow rails, and wooden nailing strips held in said slotted webs and closing the elongated slots of said rails. 95 100

In testimony whereof, I have signed this specification in the presence of two subscribing witnesses.

CHARLES H. ANDERSON.
